SUPPORT FOR NEON SIGNS

Application filed June 26, 1931. Serial No. 547,034.

Our invention relates to supports for neon signs and has particular reference to supporting devices employed in connection with raised letters supported from a background 5 in which a tubular lamp is to be employed for illuminating the surface of the letter.

In the construction of neon signs employing a background member and a raised letter or character supported in spaced relation 10 from the background, it has been the practice to provide supports for the letters which required the mechanic or assembler to have access to the rear of the background of the member in order to secure the support there- 15 to; which in the event the background was to be enclosed required unsightly openings in the base of the background member to permit access to the rear thereof.

It is, therefore, an object of our invention 20 to provide a support for such raised letter sign which is entirely accessible from the front of the sign.

Another object of our invention is to provide a support for a raised letter or character 25 in which a single supporting member may be employed both for supporting the letter and for engaging and holding a tubular lamp with which the letter is associated.

Other objects of our invention will be ap- 30 parent from a study of the following specifications, read in connection with the accompanying drawing, wherein

Fig. 1 is a perspective view of a portion of a sign constructed in accordance with our in- 35 vention;

Fig. 2 is an end elevational view of the sign shown in Fig. 1;

Fig. 3 is a top plan view of the sign shown in Fig. 1; and

Fig. 4 is a detail sectional view taken along line IV-IV, Fig. 3.

Referring to the drawing, we have illus- 40 trated in Fig. 1 a sign construction comprising a background member 1 which may be 45 constructed of wood, metal or other similar material having sufficient rigidity to support the sign indicia carried thereby. In the embodiment of our invention shown, the sign indicia comprises raised letters or characters 50 2 represented as being cut from a flat plate

of metal in the configuration of the particu- 5 lar data or character, or combination there- of, which may be desired. Such letter is illustrated in the copending application of John T. Northcott, Serial No. 520,852, filed 55 March 7, 1931.

For the purpose of illuminating the sign, a source of illumination, such as a tubular lamp 3 of the neon or gaseous discharge type, is bent into the configuration corresponding 60 to the letter or character comprising the sign indicia and is secured in front of and in spaced relation to the raised letter or character 2. Since it is necessary to thoroughly insulate the tube from the metal of the sign, 65 as well as to maintain the same in spaced relation to the letter or character, the tubular lamp 3 is mounted upon glass posts 4 secured in some manner either to the back- 70 ground or to the letter itself.

By referring to Figs. 2 and 3, it will be observed that the letter or character 2 is provided with a plurality of perforations 5, one of which is provided at each of the points at which it is desired to support the tube 3. Alongside each of the perforations 5 a strap or lug 6 is secured to the rear surface of the letter 2 to provide a space between the strap and the letter for the reception of a tongue 7 constituting one leg of a 75 Z-shaped letter support 8. The other leg 9 of the letter support 8 is illustrated as being turned in the opposite direction and provided with an opening 10 through which a suitable securing device, such as a screw 80 85 11, may pass to engage the background mem- 11, may pass to engage the background mem- ber 1 and thereby secure the support 8 to the background member.

It will be observed that the arrangement 90 of the legs 7 and 9 of the support 8 is such that when the leg 7 is inserted in the strap 6 the leg 9 will be aligned with the opening or perforation 5 in the face of the plate 2 so that ready access to the screw 11 may be had without the necessity of reaching behind 95 the plate. In other words, the screw 11 may be manipulated by means of a screw- driver which may be inserted directly through the plate 2.

Referring again to Fig. 3, it will be ob- 100

served that the vertical portion of the Z-shaped support 8 is provided with a pair of annularly extending legs 12 arranged to surround and engage the cylindrical end of the glass neon tube support 4. The cylindrical portion of the neon tube support 4 also passes through the perforation 5 so that when the same is assembled upon the letter support 8 the lateral shifting of the letter, relative to the support 8, is prevented by engagement of the glass support with the sides of the perforation 5.

The details of the glass support 4 and the manner in which it is engaged by the lugs 12 is clearly illustrated in the copending application of Ralph C. Hyde, Serial No. 450,589, filed May 7, 1930, which discloses the glass support arranged with a slot engaging the lugs 12 so that when the same is inserted in the lugs 12 and rotated to position to permit the neon tube 3 to be tied, as by means of wire 13, to the head of the glass support, the glass support 4 is locked in the lugs 12 against removal.

It will be observed, therefore, that we have provided a support for a letter or character to be carried in spaced relation upon a background and in which the support may be attached to both the letter and the background without the necessity of providing openings in the background or in the letter for the purpose of obtaining access to the attaching devices.

It will also be observed that the employment of the strap 6, secured to the back of the letter 2, obviates the necessity of permanently securing the support 8 to the letter and hence the letters with their straps attached are relatively flat and may be readily stacked in the warehouse in compact relation.

While we have illustrated and described the preferred embodiment of our invention, we do not desire to be limited to any of the details shown or described herein, except as defined in the appended claims.

We claim:

1. In a sign construction, a background member, a character comprising sign indicia formed from a relatively flat plate of suitable material, a perforation in said plate a support secured to said plate having an opening therein for receiving means for attaching the support to the background, said opening being aligned with the perforation in said plate, a tubular lamp for mounting on the exterior face of said plate and a support for said tubular lamp extending through said perforation.

2. In a sign construction, a background member, a character constituting sign indicia formed from a relatively flat plate of material, a support for securing said plate to said background comprising a substantially Z-shaped supporting element, means for at-

taching the top leg of said Z-shaped support to said plate, attaching means passing through the other leg of said support, and a perforation in said plate aligned with said attaching means for permitting access to said attaching means from the exterior of said plate, a tubular lamp for mounting on the exterior face of said plate and a support for said tubular lamp extending through said perforation.

3. In a sign construction, a background member, a character constituting sign indicia formed from a relatively flat plate of material, a support for securing said plate to said background comprising a substantially Z-shaped supporting element, means for attaching the top leg of said Z-shaped support to said plate, attaching means passing through the other leg of said support, a perforation in said plate aligned with said attaching means for permitting access to said attaching means from the exterior of said plate, a tubular light source for illuminating said plate, and an insulating support for said light source and means on said plate support for engaging said insulating support to mount said lamp upon said plate.

4. In a sign construction, a background member, a character constituting sign indicia formed from a relatively flat plate of material, a support for securing said plate to said background comprising a substantially Z-shaped supporting element, means for attaching the top leg of said Z-shaped support to said plate, attaching means passing through the other leg of said support, and a perforation in said plate aligned with said attaching means for permitting access to said attaching means from the exterior of said plate, a tubular lamp for illuminating said plate, lugs formed on said support constituting an annulus aligned with the perforation in said plate, and an insulating support for said tube extending through said perforation and engageable by said lugs.

5. In a sign construction, a background member, sign indicia comprising characters formed from a relatively flat plate of material, means for mounting said character in spaced relation upon said background including a relatively Z-shaped supporting element, a strap secured to the rear of said character for receiving between the strap and the character one of the outer legs of said Z-shaped support, means passing through the other leg of said Z-shaped support for attaching said support to said background member, and a perforation through said character aligned with said other leg to permit access to said securing means through said character.

6. In a sign construction, a background member, sign indicia comprising characters formed from a relatively flat plate of material, means for mounting said character in

spaced relation upon said background including a relatively Z-shaped supporting element, a strap secured to the rear of said character for receiving between the strap and the 5 character one of the outer legs of said Z-shaped support, means passing through the other leg of said Z-shaped support for attaching said support to said background member, a perforation through said character aligned with said other leg to permit 10 access to said securing means through said character, and a pair of lugs formed on the middle leg of said Z-shaped support and extending laterally therefrom to form an annulus aligned with the perforation in said plate.

7. In a sign construction, a background member, sign indicia comprising characters formed from a relatively flat plate of material, means for mounting said character in spaced relation upon said background including a relatively Z-shaped supporting element, a strap secured to the rear of said character for receiving between the strap and the 20 character one of the outer legs of said Z-shaped supports, means passing through the other leg of said Z-shaped support for attaching said support to said background member, a perforation through said character aligned with said other leg to permit access to said securing means through said character, and means formed on said support for engaging an insulating support passing through said perforation, and a tubular lamp 25 secured to said insulating support.

Signed at Los Angeles, California, this 6th day of June, 1931.
